INJECTION INSTRUMENT

Robert H. Alexander, Warren, Pa., assignor, by mesne assignments, to Sylvania Electric Products Inc., Wilmington, Del., a corporation of Delaware

Filed Oct. 25, 1955, Ser. No. 542,698

6 Claims. (Cl. 128—216)

This invention relates to an injection instrument and more particularly to a self-injection type hypodermic needle and its associated fluid chamber and support.

Self-injection hypodermic syringes or capsules usually employ a needle and an injecting fluid such as insulin enclosed within a resilient plastic shell. Initial pressure on the exterior of the shell causes the needle to pierce the shell, and continued pressure forces the fluid through the needle. Generally, this needle is formed as a seamless drawn tubing. One end of the tubing is shaped to provide the needle point, while the other end is crimped to a stamped washer type base member. Self-injection needles having this structure are expensive to fabricate, and since it is employed in a throw-away type instrument, the cost of the complete syringe is an important factor.

It is, therefore, an object of the invention to provide an injection instrument which is economical to produce.

A further object is the provision of an improved self-injection instrument and capsule.

A further object is to provide a self-injection instrument having a needle inlet port arranged to allow unrestricted fluid flow through the needle.

Another object is the provision of a method for producing an improved injection instrument.

A still further object is the provision of an injection instrument having a needle which can withstand a substantial lateral force.

The aforementioned objects are achieved in one aspect of the invention by providing a metal blank formed with a base and a tab which terminates in a needle section.

For a better understanding of the invention, reference is made to the following description, taken in conjunction with the accompanying drawings in which:

Fig. 1 is a plan view of a metal blank layout of the instrument constituting one embodiment of the invention;

Fig. 2 is a perspective view of the instrument made from the metal blank shown in Fig. 1; and

Fig. 3 illustrates the instrument employed with a self-injection hypodermic capsule.

Referring to the drawings, an injection instrument 11, made from a blank of flat stock such as stainless steel, is shown in layout form in Fig. 1 as having a circular base portion 13 and an elongated member or tab 15 with three integral sections 17, 19, and 21. Section 17 is formed with a crook so that it terminates along a portion of one side of the triangular brace section 19. Extending from section 19 and axially aligned therewith is the elongated needle layout section 21.

Instrument 11 may be made with any conventional metal blanking and forming apparatus such as one employing a precision progressive die. Section 17 is first folded back upon base 13 so that triangular brace section 19 is disposed near the central portion of the base. Section 19 is then bent upwardly to provide for extension of sections 19 and 21 along a plane substantially normal to base 13. The free end of triangular brace section 17 is subsequently turned to form a V-shaped rib which serves

2

as the support for elongated end section 21. The edges of end section 21 are then formed so that they abut one another to provide a needle terminating in the instrument point 23. The needle outlet 25 formed by this turning operation serves to outwardly convey the injecting fluid supplied through the inlet port 26 which is spaced above base 13. If desired, base 13, brace 19, or section 21 may be made stronger by providing the blank with thicker material in selected sections or by forming the blank with excess tab material so that it can be folded back and four several times to form these sections.

Fig. 3 shows a self-injection syringe 27 which has a cup-shaped well 29 and a closure member 31. The syringe is made of a resilient plastic material such as polyethylene which may be sealed along the lip of cup 29 and the edge of closure 31 by any convenient means such as by heat and pressure. Enclosed within the capsule is an injection fluid 33 and instrument 11. Integral with the base of cup 29 is a ledge 35 which surrounds and engages base 13 of instrument 11. The instrument base is forced under ledge 35 to effectively position and maintain instrument 11 within the walls of cup 29.

After the instrument has been mounted upon cup 29 as described above, the cup is filled with the desired injection fluid and is subsequently sealed with closure member 31. It can be seen that the capsule structure made in this manner enables the parts to be sterilized and sealed and later an injection to be made without any further handling of the injecting fluid or needle.

30 A self-injection capsule constructed in accordance with the embodiment shown is more economical to produce, and is safer to use. Due to the manner in which brace 19 is attached to base 13 by tab section 17, the needle is provided with a firm but yieldable mounting. Therefore, 35 a twisting or turning of the capsule during the injection period will not snap off the needle. In addition, a lateral pressure on the needle after it has been extended through closure 31 as far as possible will cause less strain on the needle since the closure member will absorb some of the force and provide a fulcrum point at the upper edge of brace 19 rather than near base 13. Also, since inlet port 26 is spaced above base 13 in the embodiment shown, mis-handling of the capsule will not prevent a free flow of fluid through the needle. Regardless of the location 40 or amount of pressure on cup 29, the fluid has access to the unrestricted opening.

Although one embodiment of the invention has been shown and described, it will be understood by persons skilled in the art that variations and modifications may be 45 made without departing from the scope of the invention as defined by the appended claims.

What is claimed is:

1. A method of forming an injection instrument comprising the steps of fabricating a strip of material to provide a base portion and an elongated portion having three sections, folding the first section back upon said base, bending the second section to form a brace, and turning the third section to form a hollow needle.

2. The method of forming an injection instrument comprising the steps of fabricating a strip of material to provide a base portion and an elongated portion having three sections, folding the first section back upon said base, bending the second section to form a brace extending substantially normal to said base, and turning the third section to form a hollow needle.

3. The method of forming an injection instrument comprising the steps of fabricating a strip of material to provide a base portion and an elongated portion having three sections, folding the first section back upon said base, bending the second section to form a brace extending substantially normal to said base, and turning the

third section to form a hollow needle axially aligned with said brace.

4. A method of forming an injection instrument comprising the steps of blanking a strip of metal to form a base portion having an elongated portion extending therefrom and subsequently forming said elongated portion to provide a tab folded back upon said base portion with a hollow needle extending transversely of said base portion.

5. An injection instrument formed from a metal blank comprising a base portion, a tab extending from an edge of said base portion substantially parallel thereto terminating in a brace positioned centrally of said base portion, and a hollow needle depending from said brace transverse to the base portion formed with an inlet port spaced from said base portion.

6. A self-injection capsule comprising a resilient enclosure, a fluid disposed within said enclosure, and an injection instrument mounted upon an internal wall of said enclosure, said injection instrument being formed from a metal blank and comprising a base portion, a tab extending from an edge of said base portion substantially parallel thereto terminating in a brace positioned centrally of said base portion, and a hollow needle depending from said brace transverse to the base portion formed with an inlet port spaced from said base portion.
